Fig. 5

I claim:
The ornamental design for a stuffed toy animal figure, as shown.
